UNITED STATES PATENT OFFICE.

THADDEUS W. KELTON, OF VAN BUREN, ARKANSAS.

TEMPORAL METER.

1,163,091.

Specification of Letters Patent.

Patented Dec. 7, 1915.

Application filed April 17, 1915. Serial No. 22,201.

To all whom it may concern:

Be it known that I, THADDEUS W. KELTON, a citizen of the United States, residing at Van Buren, in the county of Crawford and State of Arkansas, have invented a new and useful Temporal Meter, of which the following is a specification.

The present invention appertains to a temporal meter, and aims to provide a novel and improved appliance of that character for registering or indicating the amount of contraction of the temporal or the attrahens aurem muscles, or any other muscles, vessels, ligaments, nerves, or the like, situated 15 in the region of the temporal fossa.

The present temporal meter is adapted for use by physicians and dentists, and may be used by dentists in making artificial plates, crowns and bridgework, in that the present 20 device may be employed for determining the natural position of the jaws when the teeth are disposed in natural occlusion, and furthermore, the present instrument may be employed by physicians and dentists in cases 25 of fracture of the lower mandible or upper jaw, or in any other case where it is desired to place the teeth in occlusion.

Another object of the invention is the provision of a temporal meter embodying novel 30 means for applying the meter to the head, and having novel means for operating an indicator by the movement of the temporal muscles.

With the foregoing and other objects in 35 view which will appear as the description proceeds, the invention resides in the combination and arrangement of parts and in the details of construction hereinafter described and claimed, it being understood that 40 changes in the precise embodiment of the invention herein disclosed can be made within the scope of what is claimed without departing from the spirit of the invention.

The invention is illustrated in the accompanying drawing, wherein—

Figure 1 is a plan view of the temporal meter. Fig. 2 is a front view thereof. Fig. 3 is a longitudinal section taken approximately on the line 3—3 of Fig. 1, parts being shown in full. Fig. 4 is an enlarged front view of the indicator, portions being broken away.

In carrying out the invention, there is 55 provided an indicator 1, embodying a circular case 2, which is carried by a frame which is applicable to the head of a patient.

This frame embodies a longitudinal curved or arched spring 3 adapted to pass over the crown of the head, and having its forward end secured to the back of the case 2, the 60 forward end of the spring 3 carrying a curved plate or strip 4 adapted to rest snugly against the forehead. The rear or free end of the spring 3 carries a curved plate or strip 5 adapted to rest against the 65 back of the head, the spring 3 being flexible in order to adjust itself to the head of the patient, and to hold the frame in place upon the head. The frame also includes a transverse wire or rod 6 soldered or otherwise secured to the back of the case 2 and projecting laterally to opposite sides, the end portions 7 of the wire or rod 6 projecting angularly rearward and the ends of the rod being soldered or otherwise secured to pieces 70 75 which are in turn soldered or otherwise secured to the end portions of an arch 9 passing over the intermediate portion of the spring 3 and adapted to be disposed over the head of the wearer.

The frame carries movable actuating means, and to this end, the end portions or limbs of the arch 9 are provided with short inwardly projecting portions 10, to which actuating levers 11 are fulcrumed. The levers 11 have relatively long forwardly projecting arms and relatively short rearwardly projecting arms, and the short or rear arms of the levers 11 are provided at their free ends with transverse bearings 12 through 90 which transverse adjusting rods 13 are slidable. Buttons 14 are carried by the inner or adjacent end of the adjusting rods 13, and set screws 15 are carried by the bearings 12 for clamping the rods 13 at various 95 positions, it being noted that the rods 13 are adjustable transversely of the levers 11. The buttons 14 are adapted to rest against the temporal muscles, or other movable muscles, vessels, ligaments, nerves and the 100 like, which are to be used as a basis of operation.

The levers 11 are operatively connected to the indicator 1, and this indicator is provided with a pair of indicating or registering devices. Thus, the face plate 16 of the indicator case 2 is provided with a pair of indicating and registering dials 17 thereon, and a pair of arbors or shafts 18 are journaled through the face plate 16 at the 110 centers of the respective dials 17. Pointers 19 are carried by the forward ends of the

arbors 18 and coöperate with the respective dials, the dials being suitably graduated for the intended purposes. Each of the arbors 18 carries a relatively small pinion 20 with-
5 in the case 2, which intermeshes with a relatively large gear wheel 21 carrying a relatively small gear wheel 22. The relatively small gear wheel 22 intermeshes with a gear segment 23 carried by a lever 24 fulcrumed
10 within the case 2. Thus, each of the pointers 19 is actuated by a gear train, so that a slight or imperceptible movement of the levers 24 will impart a relatively large and noticeable movement to the pointers 19, in
15 order that the readings may be taken accurately or with precision. The levers 24 project from the bottom or periphery of the case 2, and are operatively connected to the free ends of the long arms of the levers 11,
20 by means of wire links 25 which are terminally pivoted to the levers 24 and 11. The lower or free ends of the levers 24 are normally separated by means of leaf springs
25 secured within the case and engaging the levers 24. The case 2 is provided with a stop 27 therein for limiting the movement of the levers 24 under the influence of the springs 26 whereby when the parts are released, the springs 26 will return the two
30 indicating devices to normal position, and the levers 24 being swung to normal position, will also swing the levers 11 to normal position through the medium of the links 25. The levers 24 being normally separated
35 will swing the long arms of the levers 11 away from each other, and thereby swing the short arms of the levers 11 toward one another to move the buttons 14 inwardly.

In use, the frame is applied to the head of
40 the patient, by placing the spring 3 over the head, and the spring 3 in contracting will hold the frame in place upon the head with the arch 9 straddling the head and holding the actuating devices in coöperative
45 relation with the temporal muscles. The rods 13 are then adjusted or set properly so that the buttons 14 bear properly against the temporal muscles, in order that the indicator will be properly operated by the tem-
50 ples. The parts are so set, that when the temporal muscles are contracted, as when biting with the jaws, the buttons 14 will be separated or moved outwardly, which will swing the levers 11 to thereby transmit
55 the motion to the levers 24 of the indicating devices to thereby move the pointers 19 upon the indicating dials or scales 17. When the temporal muscles return to normal position, the springs 26 of the indicator
60 will return the parts back to initial position, and in this manner, the patient under instructions from the dentist or physician will operate the indicator for determining the data desired, according to the nature of the
65 operation or work to be done.

In using the instrument, it is preferably set so that a greatest amount of movement of the indicator pointers is had, when the mouth is opened and closed, and it will be understood that the present appliance may 70 be applied to the head so as to be operated by the muscles or other suitable elements of the head which are to be used as a basis of operation.

The present device is especially useful for 75 physicians and dentists when it is desired to place the teeth in occlusion, and for similar purposes. The dentist will find the present meter of advantage in the construction of artificial plates, crowns and bridgework, 80 since the present contrivance will readily enable the dentist to determine the natural position of the jaws when the teeth are closed in natural occlusion. The device may also be used by physicians and dentists in 85 cases of fracture of the lower mandible or upper jaw, or in any cases, when it is desired to place the teeth in occlusion. In cases of indentulous mouths in order to find the proper contraction of the mouth, the mouth 90 is built up by rubber bite plates until the proper distance is found which places the jaws in normal occlusion. It is believed that the other advantages and capabilities 95 of the present appliance will be obvious to those skilled in the art, without further comment being necessary.

It will be noted that the two indicating devices are operated independently by the actuating devices, whereby the variation of 100 the movement between the temporal muscles may be detected, or whereby an average may be struck between the movements of the temporal muscles.

Another feature of the invention resides 105 in the fact that should the jaws be moved outward or sidewise to an unnatural biting position, there will be little, if any movement of the indicating devices, so that the present meter is not liable to be misleading 110 in its indications.

Having thus described the invention, what is claimed as new is:

1. In a device of the character described, 110 a frame applicable to the head, an indicator carried by the frame, and actuating means carried by the frame and operatively connected to the indicator, said actuating means being applicable to the temples or other parts of the head to be operated by the movement 115 of the muscles covering such parts.

2. In a device of the character described, 120 a frame applicable to the head, an indicator carried by the frame, and an actuating lever carried by the frame and operatively connected with the indicator, said lever being applicable to the temples or other parts of the head to be operated by the movement 125 of the muscles covering such parts.

3. In a device of the character described, a frame applicable to the head and including an arch, an indicator carried by the frame, and movable members carried by the 5 ends of the arch and applicable to the temples or other parts of the head to be operated by the movement of the muscles covering such parts, the indicator having a pair of indicating devices to which said members are respectively operatively connected.

4. In a device of the character described, a frame embodying an arch and an arched spring, the end portions of the spring having 10 means to bear against the forehead and

back of the head, an indicator carried by the frame having a pair of indicating devices, a pair of levers fulcrumed to the end portions of the arch, adjustable temple engaging members carried by the levers, and operative connections between the levers and the respective indicating devices. 20

In testimony that I claim the foregoing as my own, I have hereto affixed my signature in the presence of two witnesses.

THADDEUS W. KELTON
